UNITED STATES PATENT OFFICE.

FRED R. MOORE, OF CHICAGO, ILLINOIS.

REPAIRING DEVICE.

Application filed February 12, 1926. Serial No. 87,737.

My invention relates to a repairing device, designed especially for use in applying patches on the inner tubes of pneumatic tires, and my invention has for its main object the provision of a novel tool of this character which will be simple in construction, economical in manufacture, and highly efficient in use and which in addition may be conveniently employed in repairing all sizes of conventional tubes.

Another object of my invention is to provide a repairing tool of this kind which is characterized by having means for stretching the tube, where it is to be repaired, equally in all directions. Another object is to provide a tool in which the pressure for seating the patch will be exerted evenly thereon and in which the desired pressure may be exerted on the patch without danger of breaking either the operating tool or the tube being operated upon. Still a further object is to provide a device that may be employed with equal facility and convenience in applying either wet cement patches or heat unit vulcanizing patches.

Other objects will appear hereinafter.

The invention consists in the combinations and arrangements of parts hereinafter described and claimed.

The invention will be best understood by reference to the accompanying drawings forming a part of this specification, and in which,

Fig. 1 represents a side elevational view of a repairing device made in accordance with the present invention, the device being shown as it appears when holding the tube and when pressing a wet cement patch upon the tube;

Fig. 2 represents a view similar to Fig. 1 but showing the bridge bar detached from one of the arms;

Fig. 3 represents a top plan view of the parts shown in Fig. 1;

Fig. 4 is a longitudinal sectional view taken substantially on the line 4—4 of Fig. 3;

Fig. 5 is a sectional detail showing the presser shoe placed upon a heat unit vulcanizing patch to be applied to the tube;

Fig. 6 is a top plan view taken substantially on the line 6—6 of Fig. 5;

Fig. 7 is a vertical sectional view taken substantially on the line 7—7 of Fig. 4; and,

Fig. 8 is a vertical sectional view taken substantially on the line 8—8 of Fig. 4.

In the illustrative embodiment shown, in the accompanying drawings, 9 designates in general a base body having a substantially circular central portion 10 and contracted portions 11 and 12 which project in opposite directions. By preference, this base body is made from pressed metal and with a depending flange 13 all around as shown. The projecting portions 11 and 12 are similarly made at their free ends with elongated slots 14 and also with depending guide flanges 15 (Figs. 7 and 8.) Fixed in the flanges 13 and 15 of each of the projecting portions 11 and 12 is a pivot stud or pin 16 for pivotally carrying a swing arm presently to be described. The central portion 10 of the base body is produced or furnished with a raised portion 17 of elliptical form which, as clearly shown in the drawings, extends transversely of the base body midway between the swing arms 18 and 19 arranged on the end pivot studs 16 between the inner guide flanges 15.

The swing arm 18 curves upwardly and inwardly and carries at its extremity a pivot stud 20. This swing arm also has an upwardly projecting branch arm 21 astride of which is the yoked end 22 of a bridge bar 23, the said yoked end 22 being slotted at 24 to receive a pivot stud 25 which is passed through the branch arm 21. The opposite end of the bridge bar 23 is yoked as at 26 to pass astride the headed extremity 27 of the swing arm 19, which is also, it will be observed, curved upwardly and inwardly. In the yoked end 26 are provided bayonet slots 28 for the reception of pivot stud or pin 29 which is passed through the head 27, so that the bridge arm may be detachably connected with the swing arm 19, it being observed in this connection that the provision of the slots 24 in the yoked end 22 permits suitable adjustment of the bridge arm upon the pivot stud 25 for the ready engagement or disengagement of the yoked end 26 with the pivot stud 29 on the headed extremity 27.

30 designates a shackle ring with may be produced in any suitable manner but which as herein shown consists of two lengths of spring wire 31 and 32 suitably bowed to be placed around the raised portion 17 and having oppositely directed extremities 33 and 34 which are bound together by clip members 35. The extremities 33 are bent upwardly at an angle at 36 and curved

about pivot stud 20 whereon the shackle ring is adapted to be swung as about a pivot. The extremities 34 are bent upwardly at 37 and have secured thereto a catch plate 38 which is adapted to be engaged behind an abutment or lug 39 provided for the purpose on the headed extremity 27 so as to secure the shackle ring tightly upon an inner tube 40 upon the raised portion 17.

19 The bridge bar 23 is preferably made with an expanded central region 41 in which is fixed a bearing block 42. Tapped through the bearing block 42 is a hand operated presser screw 43 on the bottom end of which is swiveled a presser shoe 44 adapted to rest upon a suitable plate 45 which may be placed upon a wet cement patch 46 to be applied to the tube 40.

20 In the use of my improved repair device, the tube 40 to be repaired is laid lengthwise upon the elliptical raised portion 17 with the punctured or torn area positioned centrally thereof. Thereupon the swing arms 18 and 19 are moved inwardly toward each other and the shackle ring 30 is pressed down around the raised portion stretching the rubber tube uniformly in all directions and thereby opening the pores of the rubber. 25 The shackle ring is pressed down upon the rubber tube about the raised portion 17 until the catch plate 38 snaps behind lug 39 whereby the shackle ring is held in shackling position. Having thus stretched and shackled the tube upon the raised portion, the next step is to clean and roughen the rubber in the usual way by means of any suitable abrasive or rasping tool. Following this operation the cement is applied, 30 the patch 46 is placed upon the punctured or torn area, the plate 45 is placed upon the patch, and finally the bridge bar 23 is lowered and engaged with the swing arm 19 so that the desired pressure may be exerted upon the plate 45 through the manipulation 35 of the presser screw 43.

40 By making the raised portion 17 of elliptical form and by supporting the bridge arm and shackle ring by means of the inwardly and upwardly curved swing arms 18 and 19, my repair device is adapted to be employed in patching tires of any conventional size from the small sized tube for the tire used in connection with vehicles of the Ford type, to the largest size of tubes for tires of the balloon type. In the drawings, where I have illustrated a conventional tube of the smallest size, it will be seen that by making the raised portion 17 elliptical in form, the margins 47 of the tube will 45 overhang sufficiently to be properly engaged by the shackle ring for effecting the stretching and clamping action. By making the swing arms 18 and 19 curved as shown, a balloon type of inner tube may be patched 50 with equal facility since there is abundant

space between the raised portion and the swing arms to accommodate the marginal edges of the tube without curling or folding the same.

55 In Figs. 5 and 6, I illustrate my presser shoe as placed upon a heat unit vulcanizing patch 48 to be applied to the tube 40. The shoe 44, for use in this connection, comprises an elongated plate with depending edge flanges 49 which are adapted to rest upon a metallic rim 50 of the heat unit vulcanizing patch so that the heating material 51 of the unit may be permitted to burn freely while pressure is being applied by the shoe; and the top of the shoe is suitably provided with air openings 52 in order to avoid smothering of the burning material.

60 While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

65 Having described my invention, what I claim as new and desire to secure by Letters Patent is:

70 1. In a device of the class described, the combination with a base form comprising a top and continuous side wall, of instrumentality arranged to stretch an article in every direction upon said top and to clamp the article in stretched condition against said side wall, substantially as described.

75 2. In a device of the class described, the combination with a raised base comprising a top supported by a continuously rounded side wall, of means arranged to be slipped over said top and side wall and to stretch an article over said top and clamp it against said side wall, substantially as described.

80 3. In a device of the class described, a base having a raised portion comprising a top and continuous side wall, an arm on said base; and instrumentality movable on said arm for slipping over said top and side wall to stretch an article over said top and clamp it against said side wall, substantially as described.

85 4. In a device of the class described, the combination with a base having a raised portion, of a pivoted arm on said base; shackle means movably pivoted on said arm for stretching and securing an article to be patched upon said raised portion; and means on the base for fastening the shackle means, substantially as described.

90 5. In a device of the class described, the combination with a base having a raised portion, of a pivoted arm on said base; a shackle member pivoted at one end to said arm and adapted to be placed around said

raised portion; and means associated with said base for securing the free end of the shackle member, substantially as described.

6. In combination, a base provided with a raised portion; and a shackle ring supported for pivoting movement upon said base and adapted to be placed about said raised portion to stretch and shackle a tube thereon, substantially as described.
- 10 7. In combination, a base provided with a raised portion; two arms pivotally attached to said base at opposite sides of the raised portion; a bridge bar arranged to connect said arms; a shackle device pivotally connected to one arm and adapted to extend around said raised portion to stretch and shackle a tube thereon; and means associated with the bridge bar for pressing a patch upon the tube, substantially as described.
- 20 8. In a combination, a base provided with a raised portion; two arms pivotally attached to said base at opposite sides of the raised portion; a bridge bar arranged to connect said arms; a shackle device having pivoted connection with one arm and adapted to extend around said raised portion to stretch and shackle a tube thereon; cooperative means on the shackle device and the other of the arms for securing said device in fixed position; and means associated with the bridge bar for pressing a patch upon a tube, substantially as described.

9. A device of the class described comprising an elongated base; arms pivoted at the extremities of said base to swing toward and away from each other; an elliptical raised portion on said base arranged transversely thereof at a point between said arms; a shackle device swingable on one arm and adapted to extend around said raised portion and to be engaged by the opposite arm; and a bridge bar arranged to connect one arm with the other, substantially as described.

10. A device of the class described comprising an elongated base, arms pivoted at the extremities of said base to swing toward and away from each other; an elliptical raised portion on said base arranged transversely thereof at a point between said arms; a shackle device swingable on one arm and adapted to extend around said raised portion and to be engaged by the opposite arm; said arms being curved upwardly and inwardly from the base to provide spaces for the repose of the margins of the tube shackled lengthwise upon the raised portion; and a bridge bar arranged to connect one arm with the other, substantially as described.

In testimony whereof I have signed my name to this specification.

FRED R. MOORE.
